PAPER ROLL HOLDER AND DISPENSER

Lynn H. McClintock, Los Angeles, and Neil B. Currier, Wilmington, Calif.; said Currier as signor to said McClintock

Application April 20, 1937, Serial No. 138,050

14 Claims. (Cl. 242—55.5)

This invention is a paper roll holder and dispenser having a cutter or straight edge member associated therewith, of a type used in stores for holding rolls of wrapping paper.

5 Among the more important features of applicants' device is an improved means for mounting and holding a roll of paper in the supporting member, novel tensioning means for the paper cutter member and additional means of new design to enable an operator to readily remove and replace said tensioning means. One of the advantages to be derived from the novel tensioning structure for the cutting member lies in the fact that the cutting member is held under considerable tension against the paper roll whereby, when paper is being cut therefrom, the roll is held substantially immovable during such operation.

More specifically, the novel tensioning means comprises one or more flat springs, which can be readily inserted and removed without disassembling the holder proper. The flat springs are preferably assembled in bundles of two, three or four and by selecting the appropriate number of springs, the spring tension can be readily varied in accordance with requirements. Also the fact that these springs can be readily removed and replaced facilitates the renewal of the springs whenever they need to be renewed.

In the preferred embodiment of the invention, 30 the cutter bar which is resiliently pressed against the roll of paper has a slight freedom of movement so that it will readily conform to irregularities that may exist in the surface of the paper roll, whereby a clean cutting or tearing of the paper transversely is achieved in spite of such irregularities.

Another feature of the invention is that the supporting standards or housings are provided with downwardly inclined grooves or recesses for the 40 axle of the paper roll, said recesses terminating in supporting sockets, whereby said axle rolls by gravity down these recesses and positions itself almost automatically in said sockets.

Another feature of the invention is that the 45 springs bearing against the supporting arms for the cutter bar serve to support it in operative position, resiliently pressing it against the surface of the paper roll, or supporting it in an upward position, away from the paper roll, when

50 a new roll of paper is being inserted in the device.

Other details and advantages will be apparent from the accompanying drawing and more detailed description of the present preferred embodiment of the invention. In the drawing:

55 Figure 1 is a side elevation of the holder and

cutter having a roll of paper mounted therein;

Figure 2 is a side elevation having the roll of paper removed and being partly broken away;

Figure 3 is a front elevation partly broken away in the same portions as in Figure 2;

Figure 4 is a fragmentary view showing an elevation of a part of the device similar to Figure 2 with one of the spring members being removed; and

Figure 5 is a detail view of one end of one of the springs.

Referring now to the drawing, in which similar reference characters indicate similar parts, the device is for the most part constructed of sheet metal and comprises a rectangular frame member having a base 1 provided with suitable apertures 1a to fix the same to a counter and vertical side members 2 attached thereto. A top member 3, substantially U-shaped in cross section, is joined to the side members to form a rigid frame. 20 The top 3 is provided with apertures 3a whereby the frame may be suspended from the underside of a counter or shelf, if desired. Each side member 2 has extending inwardly from one side thereof a slot 4 having a widely flaring mouth 25 adapted to receive an axle 5 which rotatably supports a roll of paper. The axle is longer than the base 1, extending beyond the outer sides of members 2. The lower edge 6 of the slot 4 is inclined 30 inwardly and downwardly whereby, when the axle 30 supporting the roll of paper is mounted thereupon, the same will roll by gravity into a downwardly extending socket or recess 7 arranged at the inner end of slot 4 which is the operative position for the axle.

An overhanging projection 7a is provided at 35 one side of the recess 7 to afford a locking means for the axle 5 to prevent accidental removal of the axle from the recesses which extend considerably below the level of the edges 6 to form 40 a seat into which the axle automatically and freely drops when inserting the paper roll.

Extending parallel to the upper half of each 45 of the side members and approximately covering this area is a housing 8 having an inturned upper portion 9 integrally fixed to the top member 3. Secured to the lower edge of the housing 8 is a horizontal portion 10 having a foot 11 thereon secured to each side 2.

Since the housing 8 is spaced from each side 50 member 2, with the axle 5 being longer than the base 1, it will be seen that the housings 8 serve as suitable stop members to prevent longitudinal movement of the axle 5. Even if the roll of paper and axle 5 are carelessly aligned in the slots 4, the 55

axle will be automatically guided to the recesses 7 in view of the fact that the lower edges 6 of the slot 4 are downwardly inclined and the housings 8 will prevent longitudinal disengagement of the axle from the slots 4 or the recesses 7. This provides a relatively fool-proof structure offering many advantages over a number of the prior art structures wherein hook-like arrangements are provided with no aligning means to receive and hold 10 the axle for the paper roll.

Extending at right angles to each of the side members 2 are wings 12 which cooperate with the housing members 8 to form a substantially complete enclosure.

15 Arms 13 are pivoted between their ends by suitable trunnions 14 in bearings 15 stamped in the sides of the housing 8. The arms 13 at one end support a cutter bar or straight edge 16 which may also be defined as a plate having a tearing edge. The opposite ends of the arms 13 pivotally support rollers 17 for purposes to be explained. Suitable stub shafts or axles support these rollers which also serve to cooperate with the sides 2 to prevent dislocation of trunnions 14 from bearings 15.

30 The cutter bar 16 is provided with bracket members 16a extending at right angles thereto at each end. Each arm 13, at the end adjacent the cutter bar, is provided with a suitable aperture to receive a screw or rivet 13a. Each bracket 16a is also provided with an aperture to receive the screw or rivet 13a, these receiving apertures in the bracket and arm being in alignment and somewhat larger in diameter than the 35 screw or rivet 13a. The rivet or screw is loosely fitted in said apertures in joining the bracket and arm to permit a slight amount of play or movement between the bracket and arm. This construction will permit the arms 13 to move somewhat independently of each other, whereby the cutter bar need not necessarily move parallel to the axes of the trunnions 14. By such construction it will be obvious that if irregularities occur in the paper roll, such as the diameter of one end 40 being different from that of the other, the cutter bar will compensate for such irregularity by automatically adjusting itself to the surface of the roll at all times. This is particularly true since each arm 13 is independently urged toward the 45 paper roll by a separate spring 21 acting on each arm.

50 Rigidly secured to the inner face of each housing 8 is an anchoring member 18 provided with an upper fulcrum 19 and a lower fulcrum 20 formed by flanges bent at right angles to the body of member 18. Member 18 is spot welded or otherwise secured to the inside surface of housing plate 8. Arranged between these fulcrums and engaging the roller 17 is a spring element 21 consisting of a plurality of flat leaf springs 22. The spring element or assembly 21 is engaged on one side by the fulcrum 20 and roller 17 and about midway between on the other side by fulcrum 19. By this arrangement it will be seen that when the 55 arm 13 is swung to move the cutter bar away from the roll of paper the roller 17 will be moved inwardly, thus placing the spring 21 under greater tension.

60 The tension of the spring assembly which is composed of a plurality of leaf springs is quite great, being sufficient to hold the cutter bar against the outer contour of the roll of paper whereby, even if the roll is irregular in shape, the bar will effectively engage the roll to hold it 70 against rotary movement when paper is being

torn therefrom. This tension may be readily overcome, however, in unrolling paper, by pulling paper from the roll in a direction more or less tangential to the roll at a point engaged by the cutter bar. This is somewhat the usual manner 5 in which paper is unrolled from a roll of this sort but most of the usual paper holders do not securely hold the roll against movement while the paper is being torn or cut from the roll.

Due both to the locking projection 7a and the 10 spring pressure exerted by the cutter bar, the axle 5 will be securely held in position even when the roll of paper is nearly exhausted and, therefore, much lighter.

15 The trunnions 14 are so arranged with respect to the upper ends of the arms 13 carrying the rollers 17 that when the arms are raised to a position above the horizontal, which will be designated as the uppermost position, the rollers 17 are moved past dead center position of the 20 trunnions 14 whereby the spring elements 21 engage the rollers to hold the arms 13 and cutter bar 17 in this elevated position whereby the axle and paper roll may be readily inserted or removed.

25 The spring element 21, which is composed of 25 individual leaf springs 22, is readily replaceable by the following structure and in the following manner: Each horizontal portion 10 of the housing which encloses the spring elements is provided with an opening 23 through which the spring assembly or each individual leaf or the whole spring assembly may be readily moved endwise, either to withdraw the spring or replace it. The opening 23 is of such dimensions that a pair of thin-nosed pliers may be used to engage the end of the 30 leaves which are disposed adjacent the opening in order to withdraw the same from the housing. The withdrawal or the replacement of the springs is most easily accomplished when the arms 13 are in the position shown in Figure 4 with the roll 35 of paper and axle 5 removed. In this position the spring elements are under least tension and are substantially unflexed, whereby they offer little resistance in pushing or pulling them endwise past the fulcrums 19 and 20.

40 In replacing the leaves or assembly in the housing, the springs, being of substantially the width of the space between sides 2 and housing 8, are cammed against the innermost side 25 of arm 13 until engagement with the roller 17 is 45 effected.

45 As an alternative to engaging the ends of the spring elements by pliers, each leaf spring may be provided at the end thereof with a suitable aperture 24. Such an aperture might readily be engaged by a bent skewer or other suitable piece of wire with a bent hook on one end to effect a removal of the spring.

50 In order that accidental removal or displacement of the spring element 21 will not take place, the opening 23 is normally closed by a supplementary leaf closure member 26. This member may readily be formed from thin leaf spring material but need not be of nearly as sturdy a gage 55 as that from which the spring elements 21 are formed. The closure member 26 may be readily removed from the lower part of the housing by flexing one end of the same upwardly over the upper edge of one of the wings 12 as shown in 70 Figure 2. After removal of this member the spring element 21 may then be readily removed through the opening 23.

75 The fixed frame members of the device may be secured together in any suitable way, as by spot

welding, machine bolts, etc., but, inasmuch as once the device has been assembled it need not be disassembled even for the replacement of the springs, spot welding is preferred.

5 While the present preferred embodiment of the invention has been described in some detail, it should be understood that the invention is not limited to these details, but may be carried out in other ways, as falling within the scope of the 10 following claims.

We claim as our invention:

1. A paper dispenser comprising in combination a cutter bar, arms for supporting said cutter bar, a spring unit comprising a plurality of 15 cooperating flat springs and bearing against one of said arms for pressing the cutter bar against a roll of paper, the dispenser being provided with an aperture for the individual lengthwise insertion and removal of said flat springs for varying the pressure of the cutter bar against the 20 roll of paper.

2. A paper roll holder comprising spaced vertical members having a slot extending inwardly from one side of each member and serving as 25 supporting recesses for an axle adapted to support a roll of paper, each member having an arm pivoted thereto, each arm having a free end supporting therebetween an element having a tearing edge, each of said vertical members having a 30 housing associated therewith enclosing a spring unit cooperating with said pivoted arms to urge said element toward the paper roll, said housing also serving as stop means to prevent longitudinal movement of the axle, each spring unit being 35 composed of a plurality of leaf springs, said leaf springs being individually removable and replaceable through a suitable opening provided in each housing to vary the pressure of the element having a tearing edge against the paper roll.

40 3. A paper roll holder comprising spaced vertical members having a slot extending inwardly from one side of each member and serving as supporting recesses for an axle adapted to support a roll of paper, each member having an arm 45 pivoted thereto, each arm having a free end supporting an element having a tearing edge therebetween, each of said vertical members having a housing associated therewith enclosing a spring unit cooperating with said pivoted arms to urge 50 said element toward the paper roll, said housing also serving as stop means to prevent longitudinal movement of the axle, each spring unit being composed of a plurality of leaf springs, said leaf 55 springs being individually removable and replaceable through a suitable opening provided in each housing to vary the pressure of the element having a tearing edge against the paper roll and each leaf spring having an aperture in the end thereof nearest the housing opening 60 whereby said apertures may be engaged by a suitable tool to assist in withdrawing said leaves through said opening.

4. A paper roll holder comprising spaced vertical members having a slot extending inwardly 65 from one side of each member and serving as supporting recesses for an axle adapted to support a roll of paper, each member having an arm pivoted thereto, each arm having one free end supporting an element having a tearing edge there- 70 between, the opposite ends of said arms having rollers rotatably mounted thereon, each of said vertical members having a housing associated therewith enclosing a spring member comprising a plurality of leaf springs removably anchored 75 between two fulcrum members in each hous-

ing, one end of each spring member cooperating with said pivoted rollers on the arms, whereby said element having a tearing edge is urged against the contour of the paper roll at all times.

5. A paper roll holder comprising spaced vertical members having a slot extending inwardly from one side of each member and serving as supporting recesses for an axle adapted to support a roll of paper, each member having an arm pivoted thereto, each arm having one free end 10 supporting a plate having a tearing edge therebetween, the opposite ends of said arms having rollers rotatably mounted thereon, each of said vertical members having a housing associated therewith enclosing a spring member comprising 15 a plurality of leaf springs removably anchored between two fulcrum members in each housing, one end of each spring member cooperating with said pivoted rollers on the arms, whereby said plate is urged under tension against the contour 20 of the paper roll at all times, said springs being under greatest tension when the roll of paper is largest, and under least tension and substantially unflexed when said plate is in its innermost position, whereby the springs may be readily 25 withdrawn from engagement with the rollers and the fulcrum members through a suitable opening provided in each housing.

6. A paper roll holder comprising spaced vertical members having a slot extending inwardly 30 from one side of each member and serving as supporting recesses for an axle adapted to support a roll of paper, each member having an arm pivoted thereto, each arm having one free end supporting a plate having a tearing edge 35 therebetween, the opposite ends of said arms having rollers rotatably mounted thereon, each of said vertical members having a housing associated therewith enclosing a spring member comprising a plurality of leaf springs removably anchored 40 between two fulcrum members in each housing, one end of each spring member cooperating with said pivoted rollers on the arms, whereby said plate is urged under tension against the contour of the paper roll at all times, said 45 springs being under greatest tension when the roll of paper is largest, and under least tension and substantially unflexed when said plate is in its innermost position, whereby the springs may be readily withdrawn from engagement with the 50 rollers and the fulcrum members through a suitable opening provided in each housing, said housings being provided with supplementary leaf closure members located under said openings to prevent accidental removal of said springs. 55

7. A paper dispenser comprising in combination a cutter bar, arms supporting said cutter bar, a flat spring bearing against one of said arms for pressing the cutter bar against a roll of paper, and a housing enclosing said spring structure and retaining the same against lateral displacement, the housing being provided with an aperture for the lengthwise insertion and removal of said spring. 60

8. A paper dispenser comprising in combination a cutter bar, arms supporting said cutter bar, a flat spring bearing against one of said arms for pressing the cutter bar against a roll of paper, a housing enclosing said spring structure and retaining the same against lateral displacement, the housing being provided with an aperture for the lengthwise insertion and removal of said spring, and removable means closing said aperture to assist in retaining the spring against vertical dislodgement. 65 70 75

9. A paper dispenser comprising in combination a cutter bar, arms for supporting said cutter bar, spring retaining members, spring units each comprising a plurality of cooperating flat springs bearing at one end against said arms for pressing the cutter bar against a roll of paper and at the other end against a retaining member, a fulcrum approximately midway of each spring unit to tension same, the spring unit being retained in place when under tension by its own spring action against the arms, the retaining member and the fulcrum, the spring units being so arranged that in one position of the arms the tension on said spring units is relieved whereby the individual flat springs may be inserted or withdrawn to vary the strength of each spring unit.
10. A paper dispenser comprising spaced vertical supports, an axle mounted in the supports for carrying a roll of paper, arms pivoted to the supports, a paper cutting member extending between the arms at one end thereof, leaf springs fulcrumed on the supports, one end of the springs bearing against the arms at their ends opposite the cutting member to tension the cutting member against a roll of paper on the axle.
11. A paper dispenser comprising spaced vertical supports, an axle mounted in the supports for carrying a roll of paper, arms pivoted to the supports, a paper cutting member extending between the arms at one end thereof, a spring unit mounting on each of said vertical supports adapted to engage leaf spring units on opposite sides thereof at spaced points, leaf spring units supported by said mountings and fulcrumed thereon by the engagement thereof as specified, one end of the spring units bearing against the arms at their ends opposite the cutting member to tension the cutting member against a roll of paper on the axle.
12. A paper dispenser comprising spaced vertical supports, an axle mounted in the supports for carrying a roll of paper, arms pivoted to the supports, a paper cutting member extending between the arms at one end thereof, leaf springs fulcrumed on the supports, one end of the springs bearing against the arms at their ends opposite the cutting member to tension the cutting member against a roll of paper on the axle, the arms being adapted to swing upwardly against action of the springs past dead center and be held thus by action of the springs when it is desired to insert a new roll of paper.
13. A paper dispenser comprising spaced vertical supports, an axle mounted in the supports for carrying a roll of paper, arms pivoted to the supports, a paper cutting member extending between the arms at one end thereof, leaf springs fulcrumed on the supports, one end of the spring bearing against the arms at their ends opposite the cutting member to tension the cutting member against a roll of paper on the axle, the arms being adapted to swing upwardly against action of the springs past dead center and be held thus by action of the springs when it is desired to insert a new roll of paper, and a stop on the vertical supports to prevent upward movement of the arms beyond the desired point.
14. A paper dispenser comprising in combination a cutter bar, arms for supporting said cutter bar, spring retaining members, spring units each comprising a plurality of cooperating flat springs bearing at one end against said arms for pressing the cutter bar against a roll of paper and at the other end against a retaining member, a fulcrum approximately midway of each spring unit to tension same, the spring unit being retained in place when under tension by its own spring action against the arms, the retaining member and the fulcrum.
